[57] CLAIM

The ornamental design for a combined saddle and tack caddy, as shown and described.

DESCRIPTION

FIG. 1 is an exploded perspective view of the combined saddle and tack caddy showing my new design with the door partially open;

FIG. 2 is a front elevational view thereof, the rear being a mirror image of the front shown in FIG. 2;

FIG. 3 is an end elevational view thereof;

FIG. 4 is an end elevational view thereof;

FIG. 5 is a top plan view thereof; and,

FIG. 6 is a bottom view thereof.
